UNITED STATES PATENT OFFICE.

FERDINAND M. THEISEN, OF WAUMANDEE, WISCONSIN.

RACK-AND-PINION MECHANISM.

1,133,415.

Specification of Letters Patent.

Patented Mar. 30, 1915.

Application filed January 26, 1914. Serial No. 814,472.

To all whom it may concern:

Be it known that I, FERDINAND M. THEISEN, citizen of the United States, residing at Waumandee, in the county of Buffalo and State of Wisconsin, have invented certain new and useful Improvements in Rack-and-Pinion Mechanisms, of which the following is a specification, reference being had to the accompanying drawings.

10 This invention relates to certain improvements in rack and pinion mechanisms; and an object of the invention is to provide a device of this general character having novel and improved means whereby a tiltable or rocking body may be swung upon its support with convenience and facility under the influence of a reciprocating member.

With the above and other objects in view, 20 the invention consists of certain novel details of construction and combination of parts hereinafter fully described and claimed, it being understood that various modifications may be made in the minor details of construction within the scope of the appended claims.

In the accompanying drawings illustrating an embodiment of the invention: Figure 1 is a longitudinal sectional view illustrating a tiltable body having engaged therewith an operating mechanism constructed in accordance with my invention, said operating mechanism being indicated in fragment; and Fig. 2 is a view in elevation of 30 the opposite extremity of the operating member as disclosed in Fig. 1 and in a position different from that shown in Fig. 1, the parts coating with the operating mechanism being shown in elevation and in section.

In the accompanying drawings, 17 denotes a body mounted for tilting or swinging movement. For imparting tilting or rocking movement to the member 17 in one 40 direction, a rod 44 is pivotally connected at one end to the rear wall of the member 17 as shown at 45 and is provided at the front end with a rack 46 which is adapted to mesh with a pinion 47 carried by the rotatably supported shaft 30 with a resultant carrying of the rod forwardly whereby the member 7 is tilted or rocked. The rod is engaged with and disengaged from the pinion by means of a link 49 operatively engaged to a rock lever 50 which is centrally pivoted as shown at 51 to a standard 52 car-

ried by the frame 10 and is equipped at the working end with a guide ring 53 which encircles a guide rod 54 that extends longitudinally of the top face of the rod above the rack. Upon the link 49 being moved forwardly, the rock lever moves the rod downwardly with a resultant engagement of the rack with the pinion, the guide rod 54 freely sliding through the guide eye 53 during the forward progress of the rod. The rod 44 also serves to maintain the member 17 in its inclined adjustment and for this reason such rod 44 is provided adjacent its forward end portion or more particularly upon the forward end portion of the guide rod 54 with the upstanding spaced lugs or projections 56 affording a pocket or recess 57 adapted to accommodate the lug or finger 58 carried by the standard 52 and projecting above the guide rod 54 whereby it will be seen that when the member 17 is adjusted through the medium of the rod 44 into an inclined position, the inner or free end portion of such rod will be so elevated by the lever 50 as to cause the lug or finger 58 to become seated within the pocket or recess 57 and thereby hold the rod 44 against endwise movement and thus maintain the member 17 in its horizontal position. When it is desired to permit the member 17 to drop from an inclined position to substantially a horizontal position, it is only necessary that the lever 50 be adjusted to free the lug or finger 58 from the notch when, as is thought to be clearly apparent, the rod will be free for endwise movement, it being particularly observed that the pinion 47 is positioned a sufficient distance below the finger or lug 58 as to warrant this second position without possibility of the rack 46 becoming engaged with the pinion 47 and it is also observed that the guide ring 53 is of sufficient diameter as to readily permit the lugs or projections 56 to pass therethrough.

From the foregoing description, it is though to be obvious that a rack and pinion mechanism constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not

wish to be understood as limiting myself to the precise arrangement and formation of the several parts herein shown in carrying out my invention in practice.

5. What is claimed is:

1. A device of the character described comprising a member mounted for rocking movement, a rack pivotally connected to an extremity of said member, a driving pinion for actuating said rack, means for adjusting said rack relative to the actuating gear, spaced member carried by the rack, a lug positioned at a predetermined point above the driving pinion, and means for elevating the rack out of engagement with the pinion to position the lug between the members of the rack.
10. A device of the character described comprising a member mounted for rocking
15. A device of the character described comprising a member mounted for rocking

movement, a rack pivotally connected to 20 the member adjacent the extremity thereof, a driving pinion for actuating said rack, means for adjusting the rack operatively to the driving pinion, spaced members carried by the rack, a lug positioned at a point 25 above the driving pinion, and means for elevating the rack out of engagement with the pinion to position the lug between the members of the rack, the lug being so positioned relative to the driving gear as to permit the 30 rack to move freely between the gear and lug.

In testimony whereof I hereunto affix my signature in the presence of two witnesses.

FERDINAND M. THEISEN.
